Primary Examiner — Mark Goodwin(74) *Attorney, Agent, or Firm* — Mark S. Bicks; Alfred N. Goodman(57) **CLAIM**

The ornamental design for an electrical device cover, as shown and described.

DESCRIPTION

FIG. 1 is a top plan view of an electrical device cover showing our new design;

FIG. 2 is a front elevation view thereof;

FIG. 3 is a bottom plan view thereof;

FIG. 4 is a perspective view thereof;

FIG. 5 is a right elevation view thereof;

FIG. 6 is a left elevation view thereof;

FIG. 7 is a top plan view of a second embodiment of an electrical device cover showing our new design;

FIG. 8 is a front elevation view thereof;

FIG. 9 is a bottom plan view thereof;

FIG. 10 is a left elevation view thereof; and,

FIG. 11 is a right elevation view thereof.

The broken lines shown in the Figures are for illustrative purposes only and form no part of the claimed design.
